HAIRDRESSING TOOL

Herman C. Schlicker, Brooklyn, N. Y., assignor
to Rollocurl Corporation, New York, N. Y., a
corporation of New York

Application December 7, 1938, Serial No. 244,433

12 Claims. (Cl. 132—33)

The present invention relates to hair-dressing tools, and is more particularly directed toward hair-dressing tools embodying a disappearing comb carried in a casing or body member for lateral movement only, so as to be exposed for combing and curling the hair, or confined within the slot so that a coil of hair may be slidably removed.

The disappearing comb member which moves laterally of the slot is urged outwardly by a spring and held against accidental removal.

According to the present invention suitable means is provided whereby upon pressing the insert or comb member toward the bottom of the slot it is automatically locked in the housed position so that the wound coil of hair may be freely removed. This locking means is designed to be readily releasable so that the spring acting on the comb member will force it to the exposed position and yieldingly hold it there while the hair is being curled and combed.

The accompanying drawing shows, for purposes of illustrating the present invention, three of the many embodiments in which the invention may take form, it being understood that the drawing is illustrative of the invention rather than limiting the same.

In the drawing:

Figure 1 is a longitudinal sectional view through the hair-dressing device employing one form of lock;

Figure 2 is a transverse sectional view on the line 2—2 of Figure 1, and illustrating the locking of the insert in housed position in dotted lines;

Figure 3 is a view similar to Figure 2 showing a modified form of construction, the insert being in the locked position;

Figure 4 is a fragmentary longitudinal sectional view showing still further modified form of construction; and

Figure 5 is a fragmentary view of a still further modification designed for locking the insert in either position.

In the form of construction shown in Figures 1 and 2 the body or case is indicated at 10. It may have comb teeth 10a on the handle end, if desired. It is provided with a longitudinally extending slot 11 which opens toward the upper side of the case, as will be obvious from the drawing. This slot is adapted to receive a disappearing comb member or insert 12 having comb teeth 13 and a finger-piece 14. Immediately under the center of the finger-piece the insert is provided with a key-hole opening 15 having a small diameter portion 15', at the bottom and a large diameter portion 15" at the top.

The side walls of the case are provided with openings indicated at 16 and 17 to accommodate a plunger 18. This plunger has a large diameter portion 18' and a small diameter portion 18", and

the large diameter portion is pushed toward the insert by a coiled spring 19. The insert is urged laterally toward the exposed position by a leaf spring indicated at 20. In the exposed position of Figure 1 the tip 21 of the insert engages with an overhanging element 22 on the case, and the bottom of the opening 15 engages the plunger 18.

When one presses the insert down with the finger to the dotted line position of Figure 1, the bent spring 20 engages the lower face of the insert on each side of the plunger and hence there is no tendency for the insert to twist or turn about the plunger 18. As soon as the insert is pushed far enough down to cause the large diameter part 15" of the opening 15 to be opposite the large diameter part 18" of the plunger 18, the spring 19 acts to cause these parts to engage and lock. The teeth are effectively held inside the case so that the coil of hair may be readily removed. When pressure is applied on the end of the plunger it is moved back to release the insert so that it returns to projected position. The insert is frictionally held in projected position by pressure developed against the lower edge of the comb member by the spring 20 so that a lock in the projected position may be dispensed with.

In the device shown in Figure 3 the case or body member 30 is similar to the body member 10, except that it is here shown as being provided with laterally extending bosses 31 and 32 through which the holes 33 and 34 extend. The plunger 35 has a large diameter portion 35' and a small diameter portion 35", as indicated, the larger portion passing through the hole 33 and the smaller portion passing through the hole 34. The end of the plunger has a button 36, and a spring 37 acts to urge the plunger to the right as shown in the drawing. In this case the insert or comb member has a laterally extending opening 38 in which the large diameter portion, indicated at 39, extends to the middle of the insert. When looked at from one side the opening 38 will merely be a long opening with rounded ends, while at the other or left side, as shown in the drawing, the opening will have a keyhole contour.

With this arrangement the spring 37 will be housed in the recess 40 when the insert is in the exposed position and the end of the plunger will be accessible for manipulation.

The opening 38 and the connecting larger opening 39 form what may be called a semi-keyhole opening, in that the enlarged part 39 does not go all the way through to the other side. The enlarged part 35' of the plunger, under the influence of spring 37, snaps into opening 39 and locks the comb in retracted position. When pressure is applied manually to move the plunger to the left, Fig. 3, 35' is disengaged from 39 to re-

lease the comb, whereupon spring 20 moves it outwardly to projected position.

In the modification shown in Fig. 4 the insert 53 is slidable in the case 50 and locked in retracted position by the enlarged portion 52a of plunger 52. Plunger 52 passes through slot 55 in the comb 53 and through hole 56 in one side of casing 50. The locking effect of plunger 52 is effected by portion 52a snapping into the enlarged portion 55a formed at the top of slot 55, under the influence of spring 54 which presses the plunger toward locking position. The enlargement 55a at the top of slot 55 forms a semi-keyhole slot which cooperates with 52a in the same way that enlargement 35' in Fig. 3 cooperates with the portion 39 of the semi-keyhole slot 38, 39.

In Fig. 4 the plunger is shown in retracted and locked position, with enlargement 52a engaged in the enlarged portion 55a of the slot, thereby holding the comb locked. When it is desired to unlock the comb, the finger is pressed against the end of plunger 52, against the pressure of spring 54, to disengage 52a from 55a, and the comb is then moved outwardly to projected position by spring 20 as before.

Fig. 5 illustrates an alternative form of key-hole-shaped opening in the insert, for use when it is desired to provide a positive locking means to maintain the insert in the projected position. Instead of an enlarged opening at only one end, there are provided two enlarged openings 60 and 61, joined by a slot 62 whose width is less than the diameter of openings 60 and 61. Opening 61 cooperates with the plunger to lock the comb in projected position, while opening 60 cooperates with the plunger to lock the comb in retracted position.

The single keyhole slot 15' of Figs. 1 and 2, and 38 of Fig. 3 and 53 of Fig. 4 may be changed into 40 the double keyhole slot arrangement of Fig. 5 simply by providing the just mentioned single keyhole slots which are enlarged at one end, with the same kind of enlargements at the other end. Thereby the comb of any of the modifications 45 may be locked in projected as well as retracted positions.

It is obvious that the invention may be embodied in many forms and constructions within the scope of the claims and I wish it to be understood that the particular forms shown are but a few of the many forms. Various modifications and changes being possible, I do not otherwise limit myself in any way with respect thereto.

What is claimed is:

1. A hair-dressing device comprising a body or case having a longitudinally extending, laterally opening comb receiving slot, a comb member movable laterally of the slot so as to be exposed or to be housed within the slot so that a coil of hair may be slidably removed, a spring urging the comb member to the exposed position, a plunger slidably carried by the body and extending transversely of the slot therein and having a portion of relatively small cross section and a portion of larger cross section, the comb member having a laterally elongated opening through which the plunger passes and provided with a portion of a size to admit the smaller cross section portion of the plunger and a portion to admit only the larger portion of the plunger, and a spring urging the larger portion of the plunger toward the opening to lock the comb member in position when it enters the larger portion of the opening.

2. A hair-dressing device such as claimed in claim 1, wherein the plunger operating spring is coiled about the plunger.

3. A hair-dressing device such as claimed in claim 1, wherein the plunger operating spring extends lengthwise of the case and bears on the end of the plunger.

4. A hair-dressing device such as claimed in claim 1, wherein the elongated opening is directly opposite a finger-piece so that pressure is applied 10 in the direction of elongation of the opening.

5. A hair-dressing device such as claimed in claim 1, wherein the plunger has parts of two diameters and the opening has a narrow portion and a large diameter portion.

6. A hair-dressing device such as claimed in claim 1, wherein the portion of the opening to admit the larger cross section portion of the plunger extends partially across the comb member.

7. A hair-dressing device such as claimed in claim 1, wherein the plunger has a shoulder bearing against the side face of the comb member when in the projected position to press the other side face of the insert against the wall of the slot in the case to increase the friction between the parts and resist inward sliding of the comb member.

8. A hair-dressing tool comprising a slotted case, a comb member extending longitudinally of the slot, guides whereby the comb member may be moved laterally of the slot to projected position with the teeth of the comb member exposed or to retracted position with the teeth housed in the slot, a spring carried by the case and urging the comb member to projected position, and a spring actuated locking device for automatically locking the comb member in retracted position when pressed into that position, said locking device being manually releasable to permit the first spring to restore the comb member to projected position.

9. A hair-dressing tool comprising a slotted case, a comb member extending longitudinally of the slot, guides whereby the comb member may be moved laterally of the slot to projected position with the teeth of the comb member exposed or to retracted position with the teeth housed in the slot, a spring carried by the case and urging the comb member to projected position, the comb member having a key-hole opening, a transversely extending plunger having a small diameter portion extending through the opening and a large diameter portion adapted to enter the large diameter portion of the opening, and a spring urging the large diameter portion of the plunger against the comb member so that it enters the opening when the comb member is properly positioned.

10. A hair-dressing tool such as claimed in claim 9, wherein the large diameter portion of the opening extends partially across the comb member.

11. A hair-dressing tool such as claimed in claim 9, wherein the spring is coiled about the plunger, and the case has a recess to receive the coiled spring when compressed.

12. A hair-dressing tool such as claimed in claim 9, wherein the case has a boss extending about the large end of the plunger.
